TENSION DEVICE FOR WINDING AND LIKE MACHINES

George N. Taylor, East Providence, and John MacAlpine Ewart, Oakland Beach, R. I., assignors to Universal Winding Company, Boston, Mass., a corporation of Massachusetts

Application March 25, 1937, Serial No. 133,036

18 Claims. (Cl. 242—154)

This invention relates to improvements in tension-devices for tensioning yarn, thread and other strand materials in winding or transferring the same from a source of supply.

5 In the following specification and claims the term "yarn" is employed in a general sense to apply to all forms of strand material, whether textile or otherwise, and the designation "package" is intended to indicate the product of the 10 winding machine whatever its form.

One object of the invention is to provide a tension-device having opposed members with fingers or bars for applying resistance to the draft on the strand as it feeds therebetween and means 15 for positively maintaining the members in parallel relationship during lateral movement toward or away from each other whereby to apply uniform tension on the strand drawing between the members.

20 Another object of the invention is to provide in a winding machine a tension-device of the type indicated with means controlled by the growth in the winding to reduce the applied tension on the yarn as its lineal speed increases whereby to 25 maintain the ultimate tension at the package uniform throughout the winding.

Another object of the invention is to provide a 30 tension-device of the type indicated which is of simple construction, positive in action and proof against derangement or getting out of order.

35 Further objects of the improvement are set forth in the following specification which describes a preferred embodiment of the invention, by way of example, as illustrated by the accompanying drawings. In the drawings:

Fig. 1 is a front elevational view of a conventional type of winding machine illustrating the 40 present improved tension-device as applied to use therewith; the parts of the machine and tension-device being shown in position at the commencement of the winding operation;

Fig. 2 is an enlarged front elevation of the 45 tension-device and differential controlling means therefor showing the parts in their relationship at a later stage during the progress of the winding;

Fig. 3 is a side elevation of the same;

50 Fig. 4 is a plan view of the same shown with its parts in the same relationship as illustrated in Fig. 1;

Fig. 5 is a plan view of the tension-device, part 55 sectional on line 5—5 of Fig. 2 and illustrating the means for maintaining the tension-fingers in

parallel relationship as they are moved apart during the growth of the winding;

Fig. 6 is a partial sectional view through the fingers of the tension-members taken on line 6—6 of Fig. 4 and showing the manner in which they 5 act on the yarn to apply the maximum degree of tension at the start of the winding;

Fig. 7 is a similar partial sectional view taken on line 7—7 of Fig. 5 showing the tension-fingers in more open position to apply less tension on 10 the yarn at a later stage in the winding operation; and

Fig. 8 is a part sectional plan view of the tension-device illustrating the manner in which the movable tension-member is moved away from 15 the fixed member to permit the strand to be placed between the tension-fingers in running position.

Finger- or grid-tensions employed for applying 20 tension to strand material are usually provided with a fixed or stationary member and a movable tension-member pivoted with respect to the stationary tension-member and adapted to be swung away therefrom as the lineal speed of the strand increases during the growth of the winding to lessen the pressure and reduce the tension 25 on the running strand. When the movable member is pivoted on an axis extending parallel to the path of the yarn the swinging movement of the member causes its tension-fingers to be disposed at an angle to the opposed fingers of the stationary member. That is to say, the ends 30 of the fingers remote from the pivotal axis of the movable member are separated a greater distance from the fingers of the stationary member than the ends nearest the pivot and as a result, when the yarn is slid longitudinally of the fingers during its traverse by the reciprocating thread-guide or other yarn-traversing means the 35 degree of applied tension will fluctuate intermittently. In another form of construction the movable tension-member is pivoted on an axis 40 extending at right-angles to the path of the yarn so that as it swings on this axis its tension-fingers are spaced farther apart from the stationary fingers at the point of entrance of the 45 yarn than at the opposite or delivery end and this also causes uneven tensioning on the strand during its travel through the device.

It is the aim of the present invention to overcome 50 these defects and deficiencies of previously-used devices by providing an improved tension-device in which the tension-members may be separated or moved one relatively of the other in such a manner that the tension-fingers remain 55

parallel in opposite planes. The improved tension-device comprises, in general, a fixed tension-member, a supporting member hinged or pivoted with respect to the fixed member, a movable tension-member pivoted on the supporting member and movable therewith, means actuated by the growth in the winding for swinging the supporting member and movable tension-member on their respective pivots, and means for maintaining the movable tension-member in parallel relation to the fixed tension-member during its movement with its supporting member.

Referring to the drawings, a preferred embodiment of the improved tension-device is illustrated in Fig. 1 as applied to use on a machine for winding thread, yarn and other textile materials into cops, cones, cheeses and other forms of packages. It is to be understood, however, that the present invention is applicable to use with other types of textile machines for applying tension to various kinds of materials.

The winding machine illustrated in Fig. 1 comprises a main frame 2 provided with bearings for a rotatable winding-spindle 3 for supporting a suitable cop-tube C on which the package is wound. The yarn is traversed longitudinally of the winding-spindle 3 by means of a reciprocating thread-guide 4 which is carried by a horizontal traverse-bar or rod 5 mounted to slide in a track or guideway in a swinging traverse-frame 6. The guide 4 may be reciprocated from a helical cam, not herein shown, and the traverse-frame 6 is pivotally mounted on the cam-shaft 7 to swing about the axis of the cam to adapt the guide to recede from the winding-spindle 3 as the cop or package is built up thereon. Suitable instrumentalities are provided for manually starting the operation of the machine and for automatically arresting its operation when the strand breaks or its supply becomes exhausted, these devices being indicated in Fig. 1 of the drawings but not herein described as they form no part of the present invention.

The thread-guide 4 is normally maintained in contact with the surface on which the winding is being performed by means of a counterbalance comprising a weight 8 fastened to the traverse-frame 6 below its pivot on the cam-shaft 7. The force of the weight 8 acts to resist the movement of the thread-guide 4 outwardly from the winding-spindle 3 during the growth in diameter of the package being wound and this resistance may be augmented through the use of a differential pressure-device as next described. As shown in Figs. 1 and 2, a lever 10, pivoted at 11 to a stationary part of the machine is connected by a rod or link 12 to a member 13 fastened to the counterweight 8 of the traverse-frame 6. The lever 10 supports a weight 15 adjustable longitudinally thereof, and as the counterweight 8 swings away from the pivot 11 of the lever the weight is swung upwardly in an arc to diminish its active pressure tending to resist movement of the thread-guide away from the winding-spindle. The arrangement of the differential pressure-means is herein shown and described in detail since it provides means for also varying the amount of tension applied to the strand as will be later explained.

The tension-device of the present invention may be mounted in any suitable relationship with respect to the winding mechanism and, as shown in Fig. 1 of the drawings, it is carried on a bracket 17 supported from an arm 18 which is fastened to the side of the machine frame 2 by

means of screws 19. The tension-bracket 17 comprises a vertical bar or upright 20 having outwardly-projecting ears or lugs 21 at its upper and lower ends. The lugs 21 form supports for a vertical rod 22, the upper end of which is held in place by a nut 23, while its lower end is bent into an elbow-shaped arm 24 seated in a notch or recess 25 in a projection 26 on the under side of the lug 21 whereby to hold the rod from turning. The arm 24 is extended downwardly and then forwardly in a horizontal portion 27 formed into a helical loop or pigtail at 28 which serves as a guide for directing the strand of yarn into the tension-device.

Mounted on the upper lug 21 of the bracket 17 is a sub-catcher or yarn-cleaner, indicated generally at 30, through which the yarn draws as it leads to the thread-guide 4 to be fed to the package being wound. The sub-catcher 30 may be of any suitable construction, being herein illustrated as of the same type as that shown and described in United States Letters Patent to E. F. Parks, No. 1,926,497, dated September 12, 1933.

In the embodiment of the invention as herein illustrated the tension-device comprises two opposite tension-plates or members 39 and 40 which are of the type known as "finger" or "grid" tensions. The plates or members 39 and 40 are formed with parallel tines or fingers 41 and 42, respectively, adapted to be disposed in alternate staggered relationship to bear against the running yarn to cause it to follow a more or less sinuous course whereby to apply resistance to its draft. The tension-plates 39 and 40 are mounted on the tension-bracket 17 in the manner as later described, one tension-plate 39 being preferably fixed and the other member 40 being movable toward and away from the fixed plate to vary the relationship of the tension-fingers and thereby control the degree of sinuosity or undulation in the course of the yarn feeding therebetween.

The tension-fingers 41 and 42 of the two tension-plates 39 and 40 are preferably stamped or shaped from the metal of the plates in concavo-convex form as indicated in Figs. 6 and 7 of the drawings to provide rounded surfaces for contacting with the yarn. Referring to Figs. 3, 5 and 8, the opposite ends of the fingers 41 and 42 may be further formed with rounded protuberances 45 which serve as abutments to define the course of the yarn across their convex faces and prevent it from whipping out from between the fingers. In accordance with a preferred form of construction, the outer and inner ends of the tension-fingers 41 and 42 are connected by integral strips 47 and 48 of the metal to provide a grid-like structure for each of the tension-plates 39 and 40. The outer strips 47 of the two tension-members are bent or folded at opposite angles to the plane of the plates so that when the members are in operative relationship they provide a trough or reentrant guideway for directing the yarn into place between the fingers 41 and 42 as it is drawn upwardly through the trough, see Figs. 4 and 5. As a further means for guiding the yarn into position between the tension-plates 39 and 40, a wire guide 49 having a V-shaped or reentrant opening is fastened to the bottom of the tension-bracket 17. The fixed tension-member 39 is mounted on the rod 22 by means of ears 53 bent to project at right-angles to the plane of its plate portion, the ears being pierced with holes for receiving the rod. A screw 54, see Figs. 75

2, 3 and 5, is inserted through a hole in the plate portion of the member 39 and threaded into an ear or lug 55 on the tension-bracket 17 to hold the member in fixed position.

As shown most clearly in Figs. 3 and 4, the opposite movable tension-member or plate 40 is carried by a pivoted supporting member or frame 60. As herein illustrated, the supporting member or hinged frame 60 comprises a vertical plate portion 61 having its upper and lower ends bent at right angles to provide lateral projections or arms 62. The arms 62 have alining holes in which are held shouldered bushings or eyelets 63 which receive the rod 22 to mount the supporting member 60 for pivotal movement thereon. As shown in Fig. 3, the eyelets 63 have reduced portions inserted through the holes in the arms 62 with their ends riveted or headed over against the outer faces thereof. The eyelets 63 abut the upper and lower faces of the ears 53 on the fixed tension-plate 39 to maintain the supporting member or frame 60 in position on the rod. The upper and lower arms 62 of the frame 60 are of generally triangular shape in plan view, as shown most clearly in Figs. 4, 5 and 8, and each arm is provided with a rolled forward edge or curved lip 65. Projecting forwardly from each arm 62 of the member 60 is an offset extension 66 provided at its end with a laterally-extending strip which is bent at right-angles to the extension to form a finger 67 and then folded upon itself in V-shaped formation as indicated at 68. The lip 65 and finger 67 serve as abutments against which the yarn is adapted to bear to restrict its sliding movement longitudinally of the tension-fingers 41 and 42. That is to say, the lip 65 and finger 67 serve as guards to prevent the yarn from getting out of position with respect to the tension-fingers 41 and 42 when the tension-members 39 and 40 are in spaced-apart relationship. When the movable member 40 is moved back to extreme position, as shown in Fig. 8, the finger 67 is withdrawn to permit the entrance of the strand between the tension-plates.

Substantially midway of their length the extensions 66 of the arms 62 on the frame 60 are perforated to receive the reduced ends of a vertical rod 70 which serves to pivotally mount the movable tension-member 40 on the supporting member or frame 60 in the manner as later explained. As shown in Fig. 3, the rod 70 is headed or riveted over at its upper and lower ends to hold it fixedly in place in the extensions 66. Projecting rearwardly from the plate-portion 61 of the supporting member 60 is an arm or wing 71 which is adapted to be engaged by a spring-pressed plunger 72 mounted to slide in the bore 73 of a bearing lug 74 formed on the side of the tension-bracket 17. The plunger 72 is formed with a reduced shank-portion 75 around which is coiled a helical spring 76 pocketed in the bore 73, the spring normally tending to force the plunger outwardly to act against the wing 71 to swing the frame 60 to carry the tension-member 40 toward the fixed tension-member 39. The plunger 72 serves merely to move the tension-plate 40 into cooperative relationship with respect to the member 39 to automatically close the device after it has been manually opened. For the purpose of limiting the outward sliding movement of the plunger 72 to provide an initial clearance between its end and the wing 71, a nut 77 screwed onto the inner threaded end of the plunger is adapted to engage the end of the lug 74; a locknut 78 being

set up against the nut 77 to hold the latter in its adjusted position.

At the top and bottom of the movable tension-plate 40 are horizontal arms 81 extending in parallel relation to the fingers or bars 42 of the plate and provided at their ends with bushings or eyelets 82. The bushings or eyelets 82 are similar to the eyelets 63, previously described, and have axial holes for receiving the vertical rod 70 whereby to pivotally mount the tension-member 40 on the supporting member or frame 60. Projecting rearwardly from the edges of the vertical marginal portions 47 and 48 of the movable tension-plate 40 adjacent the upper end thereof are ears 84, shown most clearly in Figs. 2 and 8. In the ears 84 are bearing bushings or eyelets 85 of the same type as those before described. Projecting through the bores of the bushings 85 is a wire rod 87 bent into elbow-shape and extending in a link 88 which serves as the connecting means for controlling the tension-device from the winding elements of the machine. The arm 87 of the link 88 is held from axial displacement in the eyelets 85 by a loop 83, see Figs. 3 and 5, projecting from the upper end of the tension-member 40 and overlying the elbow portion of the link.

As shown in Figs. 1 to 4 the link 88 extends substantially horizontally through a rectangular aperture 89 in the fixed tension-member 39 and a slot 90 in the side of the frame 60 with its end connected to a weighted arm or lever 95 pivoted to the pressure lever 10, previously described. One end of the lever 95 is of inverted U-shape with the opposite sides of the U provided with alining threaded holes for receiving the forwardly-extending threaded end 14 of the link 12, previously described as constituting the connecting means between the pressure lever 10 and the counterweight 8 of the traverse-frame 6. Projecting upwardly from the lever 95 is an ear 96 having a hole for receiving the hooked end 97 of the link 88. A weight 98 mounted for longitudinal adjustment on the lever 95 normally tends to swing the latter downwardly to exert a pull on the link 88 to draw the movable tension-plate 40 toward the fixed plate 39. During the operation of the winding machine, as the pressure-regulating lever 10 is gradually rocked upwardly on its pivot 11 in the manner as previously explained the lever 95 is likewise swung upwardly on the pivot 14 to reduce the effective force of the weight 98 acting through the link 88 on the tension-member 40. The force exerted by the lever 95 may be adjusted in accordance with requirements by sliding the weight 98 along the lever toward or away from its fulcrum. A spring-finger 99 on the weight 98 has a V-shaped end adapted to engage in one of a series of spaced notches 100 formed in the forward face of the lever 95 to retain the weight in adjusted position.

The method of operation of the tension-device on the winding machine is as next explained. In threading the yarn into the device the strand *y* is drawn upwardly from its source of supply and the operator may use the fingers in which the end of the yarn is grasped to force open the movable tension-member 40. This may be accomplished with one motion of the hand as the strand is drawn upwardly and led across the tension-fingers 41 on the fixed tension-member 39. The movable tension-plate 40 may be held in open position during the upward movement of the hand by drawing the fingers along its inclined portion 47 and after the strand is in place the member 40 is released to permit it to be automatically re-

turned to position with its tension-fingers 42 pressing against the strand. Fig. 8 illustrates the manner in which the tension-plate 40 is moved laterally away from the plate 39 by causing the frame 60 to swing outwardly on the pivot-rod 22. As the frame 60 is swung on its pivot 22 the tension-plate 40 pivots on the vertical rod 70 and is maintained in parallel relation to the fixed tension-plate 39 as it moves away therefrom by the arm 87 of the link 88. As the movable member is moved laterally in this manner the wing 71 on the frame 60 makes contact with the plunger 72 and telescopes the latter into the bore 73 against the action of the spring 76. When the tension-member 40 is released the plunger 72 acts against the wing 71 to swing the frame 60 back to first position to carry the tension-plate 40 into cooperative relation with the fixed plate 39. The movement of the plunger 72 is limited by the engagement of the nut 77 against the end of the bearing lug 74 so that finally the weighted lever 95 will act through the link 88 to press the tension-fingers 42 on the plate 40 against the yarn in the manner illustrated in Figs. 1, 4 and 6.

The strand of yarn *y* is drawn upwardly from the tension-device through the slot in the sub-catcher 30, thence through the slot in the thread-guide 4 and its end attached to the cop-tube C on the winding-spindle 3. At the start of the winding operation the thread-guide 4 is placed against the surface of the cop-tube C with the traverse-frame 6 assuming the position shown in Fig. 1 of the drawings. With the traverse-frame 6 in this relationship the weighted lever 95 is positioned substantially horizontal and by sliding the weight 98 along the lever the device is adjusted to apply the required degree of tension on the yarn. With the usual adjustment of the device the tension-fingers 41 and 42 assume a position in substantial alignment as illustrated in Figs. 1, 4 and 6 and the yarn *y* drawing between the fingers is caused to follow a tortuous course of maximum sinuosity.

As the machine is started to operate the winding-spindle 3 is rotated to wind the yarn onto the cop-tube C while it is traversed longitudinally thereof by the reciprocating thread-guide 4. As the package builds up on the spindle 3 it forces the thread-guide 4 outwardly therefrom with the traverse-frame 6 swinging on the shaft 7 as a pivot under this action. As the traverse-frame 6 swings in a clockwise direction, as viewed in Fig. 1, it draws the link 12 toward the left and rocks the pressure-lever 10 in a counterclockwise direction to gradually reduce the effective force of the weight 15 in resisting the movement of the thread-guide 4 in its recession from the winding-spindle 3. In this manner the pressure 60 of the thread-guide on the package is gradually relieved in proportion to the growth in the winding.

Simultaneously with the upward swinging movement of the pressure-lever 10 during the winding the tension-lever 95 is swung upwardly on the pivot 14 to reduce its effective force on the movable tension-plate 40. As the lever 95 is rocked upwardly in this manner it reduces the pressure of the movable tension-plate 40 against the yarn but does not alter the position of the plate due to the fact that the lever 95 is moved bodily to the left as the lever 10 swings upwardly. The tension-plate 40 is shifted laterally by the yarn itself which tends to straighten in its course 75 as the force exerted by the tension-lever 95 is

gradually reduced. As the movable tension-member 40 is thus separated from the fixed member 39 the resistance offered to the passage of the yarn is diminished and thereby the applied tension is reduced in proportion to the increase in its lineal speed.

As the movable tension-member 40 is shifted away from the fixed member 39 it is maintained in parallelism therewith due to its connection with the arm 87 of the link 88, see Figs. 2 and 5. During the shifting movement of the member 40 the frame 60 swings on the pivot-rod 22 as shown in Fig. 8 of the drawings.

It will be observed from the foregoing that the present invention provides a particularly simple and efficient device for applying tension to yarn, thread and other strand materials delivering to winding and other processes. The improved tension-device operates automatically to control the relationship of the tension-members during the winding of a package whereby to relieve the tension applied to the yarn as the lineal speed of the latter increases.

As a particular feature of improvement in the present invention the tension-fingers are maintained in true parallelism both horizontally and vertically throughout the winding operation. Consequently, the tension is applied to the yarn uniformly whatever its position in relation to the fingers or bars of the tension-members. That is to say, the yarn may slide back and forth on the fingers or assume different positions longitudinally thereof without causing the tension to change. On the other hand, with previously used tension-devices of the gate type where one of the tension-members is pivoted to swing about an axis, the two members are separated in angular relationship and the tension will vary as the yarn shifts toward or away from the pivot. In other words, the distance between the tension-fingers increases as the yarn shifts outwardly away from the pivot point and vice versa so that as the yarn plays back and forth along the fingers it will take a greater or less tortuous course thereover and the tension applied thereto will vary accordingly. With the present device the yarn is wound under uniform tension and therefore a more perfect and properly formed package is produced without danger of excessive compression tending to bulge and break down the wound mass or prevent free delivery of the coils therefrom when the yarn is unwound from the package.

While the device is herein shown and described as embodied in a preferred form of construction, it is to be understood that modifications may be made in the structure and arrangement of the parts of the device and in the method of applying it to use without departing from the spirit or scope of the invention. Therefore, without limiting ourselves in this respect, we claim:

1. In a device of the type indicated, the combination of a pair of relatively movable tension-members between which the strand of yarn feeds, a movable support, means for hinging one of the tension-members to the support to adapt it to rock on an axis parallel to the direction of feed of the strand, means operative to move the support to displace one of the tension-members with respect to the other tension-member, and means for maintaining the tension-members in parallel relationship during their relative displacement.

2. A tension-device comprising a fixed grid-member having substantially parallel bars, a second grid-member bodily movable with respect

- to the fixed grid-member and having bars adapted to cooperate with those of the fixed member to press against a strand to apply tension thereto, a pivoted member for supporting the movable grid-member to adapt it to move toward and away from the fixed member, and means for maintaining the movable member in parallel relation to the fixed member during its movement with the supporting member.
3. A tension-device comprising a fixed member having spaced fingers, a second member bodily movable at one side of the fixed member and having similar fingers cooperating with those on the fixed member to press against a strand to apply tension thereto, a support for the movable tension-member, means for moving said support to shift the movable member toward and away from the fixed member, and means for maintaining the movable member in parallel relation to the fixed member during its movement with respect thereto.
4. A tension-device comprising a fixed tension-member, a movable tension-member adapted to cooperate with the fixed member to press against a strand drawing therebetween, a hinged supporting member, means for pivotally mounting the movable tension-member on the supporting member to adapt it to move toward and away from the fixed tension-member, and means for maintaining the movable tension-member in parallel relation to the fixed tension-member during its movement with respect thereto.
5. In a tension-device, the combination of a fixed tension-member, a movable tension-member for cooperation with the fixed member to apply tension to a strand drawing therebetween, a hinged supporting member, means for pivotally mounting the movable tension-member on the supporting member, means for applying a force to the supporting member to cause it to move the movable tension-member toward the fixed member to apply tension to the strand, and means for maintaining the movable tension-member in parallelism with the fixed tension-member whatever its position in relation thereto.
6. In a tension-device, the combination of a fixed grid-member, a movable grid-member adapted to cooperate with the fixed member to cause a strand drawing therebetween to follow a sinuous course, a pivoted supporting member, means for mounting the movable grid-member on said supporting member to adapt it to move toward and away from the fixed member, means acting on the supporting member to move the movable grid-member toward the fixed member, and means for maintaining the movable grid-member in parallelism with the fixed member whatever its position in relation thereto.
7. In a tension-device, the combination of a fixed tension-member, a movable tension-member, means on said members for directing a strand in a sinuous course as it feeds therebetween to apply tension thereto, a supporting member pivoted on an axis parallel to the path of the strand, means for mounting the movable tension-member on the supporting member to adapt it to pivot on an axis parallel to the pivotal axis of said supporting member, means operative to swing the supporting member to move the movable tension-member toward the fixed member, and means for maintaining the movable member in parallelism with the fixed tension-member in all positions to which it is moved.
8. In a tension-device, the combination of a fixed tension-member, a movable tension-member
- adapted to cooperate with the fixed member to apply tension to a strand drawing therebetween, a swinging frame for supporting the movable member to adapt it to move toward and away from the fixed member, a rod having an angular portion connected to the movable tension-member for maintaining it in parallel relation to the fixed member, and means acting to slide the rod to cause it to move the movable tension-member toward the fixed tension-member.
9. In a device of the type indicated, the combination of a fixed tension-member having spaced fingers, a second tension-member having spaced fingers cooperating with the fingers of the fixed tension-member and bodily movable toward and away from the fixed tension-member at one side thereof to vary the tension applied to a strand drawing therebetween, means directly connected to the movable member for applying pressure thereto to adapt it to bear against the strand to apply tension thereto as it feeds between the tension-members, means for relieving the pressure on the movable member to adapt it to recede from the fixed member to reduce the tension applied to the strand, and means for maintaining the movable tension-member in parallelism with the fixed member during its movement with respect thereto.
10. In a device of the type indicated, the combination of a relatively fixed tension-member, a pivotally mounted frame, a movable tension-member hinged to said frame, means operative to swing the frame to move the movable tension-member toward the fixed member, and means for maintaining the movable member in parallelism with the fixed member during its movement with respect thereto.
11. In a device of the type indicated, the combination of a support, a tension-member fixedly mounted on said support, a frame pivoted to the support, a second tension-member pivoted to said frame, a rod having a right-angular extension engaging the second tension-member to maintain it in parallelism with the first tension-member, and means acting on the rod to cause the second tension-member to press against a strand drawing between the said members to apply tension thereto.
12. In combination with the winding mechanism of a winding machine, a tension-device comprising a pair of opposite tension-members for tensioning a strand drawing therebetween, a link directly connected to one of the tension-members, pressure-means acting on the link for normally urging the tension-members against the strand, means controlled by the growth in the winding for relieving the pressure to allow the tension-members to separate to reduce the amount of tension applied to the strand, and means for positively maintaining the tension-members in parallelism throughout their movement of separation.
13. In combination with the winding mechanism of a winding machine, a tension-device for tensioning a strand feeding to the winding mechanism comprising a fixed tension-member, a movable tension-member, a hinged member pivotally mounting the movable tension-member for movement toward and away from the fixed tension-member, pressure-means for normally urging the movable tension-member against the strand drawing between the tension-members, means controlled by the growth in the winding to relieve the pressure to allow the movable tension-member to recede from the fixed tension-member, and positively acting means for main-

taining the movable tension-member in parallel relation to the fixed tension-member during its movement with respect thereto.

14. In combination with a winding mechanism, 5 a tension-device comprising opposed tension-members having spaced fingers for applying tension to a strand feeding to the winding mechanism, a hinged member for pivotally mounting one of said tension-members to adapt it for movement with respect to the other member to vary 10 the amount of tension applied to the strand, pressure-means operative on the movable tension-member, means controlled by the growth in the winding to gradually reduce the force of said pressure-means on the movable tension-member, 15 and means for maintaining the movable tension-member constantly in parallelism with the opposed tension-member.

15. In combination with a winding mechanism, 20 a tension-device comprising a fixed tension-member, a second tension-member, a hinged member pivotally mounting the second tension-member to adapt it for movement toward and away from the fixed member to vary the tension 25 applied to the strand drawing therebetween, weighted means for normally urging the movable tension-member toward the fixed member, means controlled by the growth in the winding for diminishing the effect of the weighted means to 30 permit the movable tension-member to be displaced with respect to the fixed member to reduce the applied tension, and means for constantly maintaining the movable tension-member in parallel relation to the fixed tension-member.

35 16. In combination with a winding mechanism, a tension-device comprising a fixed tension-member, a second tension-member movable toward and away from the fixed member, said members being provided with spaced fingers for 40 directing the strand in a sinuous course to apply resistance to its draft, a weighted lever, a link

directly connecting the lever and movable tension-member and normally acting to maintain the movable tension-member pressing against the strand, and means controlled by the growth in the winding for actuating the weighted lever to gradually diminish the pressure of the movable member against the strand, said link being so constructed and arranged as to constantly maintain the movable tension-member in parallel relation to the fixed tension-member.

10 17. In combination with a winding mechanism, 15 a tension-device comprising a fixed tension-member, a pivoted supporting member, a second tension-member pivotally mounted on the supporting member and movable thereby toward and away from the fixed tension-member, weight-operated means for normally maintaining the supporting member in position to cause the movable tension-member to cooperate with the fixed member to apply tension to a strand drawing therebetween, means controlled by the growth in the winding for reducing the force of the weight-operated means to relieve the pressure of the movable tension-member against the strand, and means for constantly maintaining the movable tension-member in parallel relation to the fixed tension-member.

20 18. A tension-device comprising relatively 25 movable tension-members adapted to cooperate to press against a strand drawing therebetween, a supporting member hingedly mounted for rocking movement about an axis parallel to the direction in which the yarn feeds, means for pivotally mounting one of the tension-members on the supporting member to adapt it to move bodily 30 toward and away from the other tension-member, and means for maintaining the tension-members in parallel relationship during the relative movement thereof.
